UNITED STATES PATENT OFFICE.

HOWARD S. MELLOTT, OF MORENCI, MICHIGAN, ASSIGNOR TO BY-PRODUCTS RE-COVERY COMPANY, OF TOLEDO, OHIO, A CORPORATION OF OHIO.

EVAPORATING APPARATUS.

Application filed April 19, 1915. Serial No. 22,510.

To all whom it may concern:

Be it known that I, HOWARD S. MELLOTT, a citizen of the United States, residing at Morenci, in the county of Lenawee and State of Michigan, have invented certain new and useful Improvements in Evaporating Apparatus, of which the following is a specification, reference being had therein to the accompanying drawing.

10 This invention relates to an improved apparatus for treating substances to change the consistency thereof, and while of a character designed for use in the treatment of substances generally, is designed more especially for the evaporation or condensing of milk, milk products, and similar material or substances.

The invention has more particular reference to an apparatus invented by Charles R. Mabee, wherein is employed a cylindrical container having therewithin means for applying a layer of the substance to be treated to the surface of the container, and subjecting said layer of material, while in contact with said surface, to a rapid advancing movement over the surface, whereby there is maintained, within the layer of material, or substance, a central quiet zone for the escape of gases and vapors, means being provided for subjecting the treating surface to a temperature different from that of the material or substance under treatment.

A mechanism embodying the invention of the said Charles R. Mabee, of the sort last above referred to, is shown and described in his application, Serial No. 40,757, filed July 19, 1915.

In an apparatus of the character under consideration it has been ascertained that should portions of the substance adhere to the surface, the uniform rapid movement of the layer of substance over the surface would be thereby impeded, and the accumulation of particles of the substance or material on the treating surface will tend to remove certain portions of the layer from direct contact with the surface, thereby retarding the transmission of heat from the surface to the body of material.

50 Therefore it is desirable to remove any adhering particles of the material or substance from the treating surface, without stopping the operation of the machine, and

it is one of the primary objects of the present invention to incorporate in an apparatus of the character under consideration, novel means for continuously cleansing the surface of adhering particles of the substance, said means, however, permitting the body of the layer of material or substance to have continuous uninterrupted movement over, and while in uniform contact with, the surface.

The present invention is to be distinguished from those wherein means are employed to pick up and throw the material or substance onto the heated surface, and to immediately, thereafter, scrape the material from said surface and allow it to recede, to be again picked up, when the foregoing operation will be repeated. Nor is the present invention to be confused with that type of apparatus wherein the material is subjected to a stirring operation.

The present invention may be said to include an apparatus having novel means for applying a layer of material or substance by force to a substantially cylindrical container, having a temperature different from that of the material or substance; subjecting said layer of material or substance, while in contact with the treating surface, to rapid continuous movement thereover, and removing adhering particles from the surface during such continuous movement thereof, and without impeding said movement.

It is also contemplated by the present invention to provide a novel construction and arrangement of conveyor members, which likewise constitute means for cleansing and polishing the treating surface of the container.

It is also comprehended, by the invention, to provide means whereby the conveyor members are yieldably supported in a normal position adjacent or in contact with the inner surface of the container.

Another feature of the invention resides in a novel arrangement of conveyor members, which preferably extend longitudinally of the conveyor, and at a slight inclination, thereby assisting in the rapid continuous longitudinal travel of the material towards the outlet end of the container.

Still another feature of the invention in-

cludes novel means whereby the combined conveyor and brush members may be readily detached for cleansing purposes, replacement, etc., and without displacing any other 5 of the said sections.

Again, the invention embodies means whereby the normally yieldably supported conveyor members may be rigidly supported in adjusted positions, as desired.

10 Still further improvements and novel details in the construction and arrangement of the various parts will be appreciated from the description to follow, which, for a clear understanding of the invention, is 15 to be considered in connection with the accompanying drawings, which form a part hereof, and wherein is disclosed, for the purpose of illustration, a convenient and satisfactory embodiment of the invention.

20 In the drawings:—

Figure 1 is an elevation, partly in section, of an apparatus for the described purpose;

Figure 2 is a transverse section, and

25 Figures 3 and 4 are detail views of the conveyor and cleansing mechanism.

With more particular reference to the drawings, wherein like reference numerals refer to corresponding parts throughout the 30 several views, 1 is a container preferably cylindrical in form, and having a surrounding jacket 2, whereby to form a chamber 3, entirely surrounding the container 1, and adapted for the reception of steam or the like, whereby to impart to the surface of 35 the container, a temperature different from that of the material or substance to be treated. The container is preferably stationary, being supported in place, in any 40 desired manner, as by feet or standards 4.

In that form of apparatus illustrated in the drawings, the cylindrical container has openings 5^a and 6^a, respectively, in its ends 5 and 6, but it is to be understood that 45 one or both of the ends may be open or closed in the treatment of certain substances. A suitable collar 5^b and 6^b, respectively, projects inwardly from the end walls 5 and 6, whereby to prevent any of the 50 material running over the edges of the wall surrounding the openings 5^a and 6^a.

Positioned within the cylindrical container is novel means for engaging the substance to be treated and applying the same, 55 under centrifugal force, to the interior surface of the container, in the form of a film or layer, and for imparting movement to said layer over said surface. In the preferred embodiment of the invention this 60 same means is preferably utilized for the continuous cleansing of the interior surface of the container, and removing any particles thereof which might tend to adhere to the surface.

65 A shaft 7 is provided, the same extend-

ing horizontally and substantially centrally within the container. The container may, if desired, be arranged at a slight downward inclination towards the outlet end thereof. The shaft 7 has suitable bearings 7^a at the 70 end walls of the container, one end 8 of the shaft projecting beyond the adjacent end wall and having mounted thereon a suitable pulley 9. The pulley 9 is fixed to the shaft whereby the shaft is moved and 75 means, as a belt 10, driven in any desired manner, by mechanism not shown, is adapted to rotate the pulley and shaft at a high rate of speed, say from 200 to 500 revolutions per minute. 80

Fixed to the shaft, for movement therewith, are supporting webs 11, there conveniently being two of said webs, one adjacent each end of the shaft. One or more intermediate supports may be provided as 85 desired. Projecting between the webs 11, and secured to the periphery thereof, in any desired manner, are supporting bars 12. These bars 12 conveniently have offset terminals 12^a secured as by bolts or rivets 90 12^b to peripheral flanges 11^a on the webs 11. Any number of such bars may be employed, three being illustrated and arranged substantially equi-distant apart about the periphery of the webs 11. 95

Supported on the bars 12 are brackets 13, upon which are adjustably mounted supports 14, which latter preferably take an inverted U-shaped formation. The connection between the supports 14 and brackets 13 is preferably a movable one, the support 14 being provided with a vertically extending slotted way 13^a, and the side arms of the support 14 having projecting therefrom a pin 16 loosely engaging in said 105 slotted way. A nut 17 is provided, the same having threaded engagement with the pin and adapted to be adjusted into a position to prevent an unnecessary lateral play while permitting of relative sliding movement between the members 13 and 14. 110

While it will be appreciated that by reason of the loose support for the conveyor members the same in the rotary movement of the shaft 7 will be forced outwardly 115 by centrifugal force into contact with the surface of the container, means are provided, however, for yieldably supporting the conveyor members and to maintain the same normally adjacent to, or in contact 120 with, the surface, and with this in view suitable spiral springs 18 are employed, the same being sleeved upon pins 19, projecting between the offset flanges 14^b of the side arms of the support 14 and the horizontal bar 12. The tendency of the springs 125 is to exert outward pressure on the support 14, and cause the conveyor members to assume a position adjacent to or in contact with the surface of the container. 130

The conveyor members preferably take the form of brushes 15, the same acting, when in contact with the surface of the container, to remove adhering particles of the substance from the surface of the container. While these conveyor and cleansing brushes 15 may extend from end to end of the horizontal bars 12, satisfactory results are obtained by forming the same in relatively short sections, and in so positioning each section on the bars 12, that they successively act upon a different portion of the treating surface. There being three horizontal bars 12 illustrated, a brush section is provided for each bar, that brush adjacent the inlet end of the machine terminating at a point substantially in line with the inner end of the brush of the next succeeding bar 12, and this brush, in turn, terminating at a point substantially in line with the inner end of the brush of the next succeeding bar, which latter brush projects to a point substantially in line with the rear end web 11. In other words, the conveyor members or brushes are spaced circumferentially within the container so that portions of the successive conveyor members or brushes are spaced longitudinally from the preceding members.

In the preferred embodiment of the invention, as illustrated, the supports at opposite ends of the brush carrying frames are slightly laterally offset with respect to one another on the supports 12, whereby the brushes extend at a slight inclination or angle to the longitudinal axis of said bars 12 and therefore to the longitudinal axis of the surface of the container. Though this feature of the invention is not limited to the arrangement of brushes alluded to, it is found that this peculiar disposition of the brushes has a tendency to assist in the rapid and continuous flow of the material in layer formation towards the outlet end of the container.

It will be noted that the brushes are readily detachable for cleansing purposes, etc., by releasing the pin 16 and nut 17, and it will also be observed that by tightening the nut 17, the conveyor supports 14 which are normally, resiliently, supported, may be rigidly supported in position, and that this position may be readily adjusted by reason of the pin and slot connection 16-13^a.

A suitable valve controlled inlet 23 is provided, for steam or the like, it being understood that by adjustment of the valve 23^a, the temperature of the treating surface may be regulated at will. It is also to be borne in mind that material other than steam may be introduced into the chamber, according to the desired treatment.

A suitable outlet from the chamber is provided at 24.

The outlet for the material, after treatment, is conveniently provided in any por-

tion of the periphery of the container, but preferably adjacent the rear end thereof, and arranged tangentially, as illustrated at 25.

The operation may be reviewed as follows:—

Assuming that milk is the substance to be treated, a supply of the same is conveniently maintained adjacent the container, from which it flows through the inlet conduit 21 into the container. The shaft 7 is rotated at a high rate of speed, which differs according to the desired treatment, but which speed preferably approximates from 200 to 500 revolutions per minute. Immediately upon its delivery to the container 1 the milk is caught up by one or more of the conveyor and cleansing brushes 15, and because of the high speed at which the conveyors are rotated, the milk is applied in layer formation to the heated surface of the container, and a central quiet zone within the layer of material is always maintained. The layer or film of material is substantially uniform throughout, and the central space within the film is substantially free from the material, as distinguished from the operation of an apparatus wherein stirrers are employed to treat the material in bulk form, or wherein the material is applied to the surface and scraped therefrom to immediately fall back to the bottom of the container for subsequent treatment. The flow of the milk being substantially continuous, the application of the same to the periphery of the container continues, and through centrifugal force, there is built up on the heated surface, a layer of the material, which may vary from say one-eighth of an inch in thickness to several inches in thickness.

The brushes being driven at a high speed, as previously stated, the material will not be allowed to settle in the container, but a continuous movable layer of the material will be maintained in contact with the surface.

In the movement of the conveyor mechanism the brushes 15, acting under centrifugal force, will be moved outwardly and maintained in active contact with the interior surface of the container, with the result that the interior surface will, at all times, remain smooth and cleansed of any adhering particles.

It is also to be noted that the construction, arrangement, and movement of the brushes is such as to not obstruct or impede materially the continuity of the layer of material over the surface of the container, and the material will be moved not only circumferentially of the container but gradually lengthwise thereof towards the outlet end thereof.

The gases or vapors escape from the material into the interior quiet central zone

of the container, and find exit through the openings 5^a and 6^a in the end walls of the container.

I claim:

- 5 1. In an evaporating apparatus, the combination of a stationary cylindrical container, means for heating the wall thereof, means for introducing material to be treated into the container, a rotatable conveyor mechanism positioned within the container, said conveyor mechanism having a brushing surface extending longitudinally at an angle, and movable into contact with the surface of the container, and means for rotating the conveyor mechanism at a high speed, whereby to impart continuous and simultaneous circumferential and endwise movement to a layer of material in contact with the heating wall of the container, while 10 maintaining a central quiet zone for the inward escape of vapors from said layer, and said container having a free discharge at its end for said vapors.
- 20 2. In an apparatus of the character described, the combination of a substantially cylindrical container, means for applying to the wall thereof a temperature different from that of the material to be treated, conveyor members arranged adjacent to the inner surface of the container, and extending longitudinally thereof, spring supporting means for the conveyor members, permitting the latter to yield, and independent means for rendering said yieldable action 30 inactive.
- 35 3. In an apparatus of the character described, the combination of a cylindrical wall, means for applying to said wall a temperature different from that of the material

to be treated, conveyor members within the wall extending longitudinally thereof, means for rigidly supporting the conveyor members in position adjacent the inner surface of said wall, said means being releasable, and means for yieldably supporting the conveyor members upon the release of said means.

4. In an apparatus of the character described, the combination of a cylindrical wall, means for applying to said wall a temperature different from that of the material to be treated, brushes within the wall extending longitudinally thereof, means for rigidly supporting the brushes in position adjacent the inner surface of said wall, said means being releasable, and means for yieldably supporting the brushes upon the release of said means.

5. In an apparatus of the character described, the combination of a cylindrical container, means for applying to the wall thereof, a temperature different from that of the material to be treated, conveyor members within the container extending longitudinally thereof, adjustable means for rigidly supporting the conveyor members in a position in contact with or adjacent to the inner surface of said wall, said means being releasable, and spring means acting to support said conveyor members upon the release of said means.

In testimony whereof I hereunto affix my signature in the presence of two witnesses.

HOWARD S. MELLOTT.
